UNITED STATES PATENT OFFICE.

CHARLES E. HOPKINS, OF PLAINFIELD, NEW JERSEY.

MACHINE FOR CASTING CURVED STEREO TYPE PLATES.

Application filed February 14, 1917, Serial No. 148,523. Renewed March 21, 1922. Serial No. 545,567.

To all whom it may concern:

Be it known that I, CHARLES E. HOPKINS, a citizen of the United States, residing at Plainfield, in the county of Union and State 5 of New Jersey, have invented a new and useful Machine for Casting Curved Stereotype Plates, of which the following is a specification.

This invention relates to a machine for 10 casting curved stereotype plates, for use on the cylinders of rotary web printing presses. It is designed on simplified lines, and the principal features of the invention are:

Means on the back, independent of the 15 matrix clamps, for positioning a flexible matrix; said means provided with a single operating means; means by which the movable core is supported on a single rail or track; and means for guiding the core so 20 that it turns from a horizontal to a vertical position; means for holding the core down when the stereotype plate is being freed from its periphery; means on the back for supporting and positioning the bottom ring; 25 means on the back for supporting and positioning the core; and a supporting and guiding bracket for the core.

Further objects and advantages of the invention will appear hereinafter.

Reference is to be had to the accompanying drawings, in which

Fig. 1 is a side elevation of a preferred embodiment of the invention, showing the core in the horizontal position, and a stereotype plate above and supported by plate lifters in alignment with plate guide-ways on the finishing mechanism;

Fig. 2 is a plan view of the machine with the core in the vertical casting position, a portion of the gearing is broken away to better illustrate;

Fig. 3 is a cross section on line 3—3 of Fig. 1 looking toward the casting back, or rear;

Fig. 4 is a longitudinal section on line 4—4 of Fig. 2, the core being shown tilted at an angle away from the casting back with a stereotype plate cast upon its periphery;

Fig. 5 is a similar section on enlarged scale showing the mold closed;

Fig. 6 is a cross section on the line 6—6 of Fig. 2 with the core in casting position within the back's concavity;

Fig. 7 is a side view of the core supporting

and guiding bracket, and the mechanism for moving the matrix clamping and core locking means;

Fig. 8 is a cross section of the mold in casting position;

Fig. 9 is a similar view with the matrix clamping and core locking means moved into unlocked position;

Fig. 10 is a cross section taken on line 10—10 of Fig. 2, looking toward the finishing mechanism;

Fig. 11 is a cross section on the line 11—11 of Fig. 2 with the parts in the position in which the riser is starting to descend;

Fig. 12 is a front end view looking toward the casting mechanism, part of the gearing being broken away to better illustrate;

Fig. 13 shows a fragment of the knife shaft driving gear and illustrates how the saw bracket can be moved toward or away from the axis of the knife shaft, and

Fig. 14 is a plan view of Fig. 13.

The invention is illustrated as embodied in a machine having a vertically disposed concave back 10, supported between side frames 11 and 12. Fixed along each side of the back 10 are vertical locking strips 13. These locking strips are formed with locking recesses 14 parallel and facing the straight sides of the concavity of the back; see Figs. 4 and 8. Between the locking recess 14 and the edge of the back is located a bolster packing strip 15. This packing strip is formed with a tongue 16 which is positioned in a slot formed in the underside of the locking strip 13, and holds the packing strip in position. The packing strip is beveled off at the back or outer edge so that it can pivot away from the back's concavity.

Each locking strip 13 has formed on it three angular projections 17, upon which are slidably attached matrix positioning slides 18 on each edge of the back. The slides 18 are operated by rock arms 19, fast on vertical shafts 20, which are located in bearings 100 formed on the locking strip 13. Each of the vertical shafts 20 has a rock lever 21 fast on its bottom end, the free ends of which levers engage in a bearing formed in vertically disposed rock levers 22 and 23, which are made fast on the ends of a cross shaft 24, located in bearings in the side frames 11 and 12. A handle is formed on the free end of rock lever 23 for operating this slide mechanism to move the said matrix posi-

tioning slides toward or away from the back's concavity simultaneously. (See Figs. 3, 6, 8 and 9.)

A casting chamber bottom closing and 5 core supporting segmental ring or end member 25, is located at the bottom and within the concavity of the back 10. This ring 25 is supported by pivots 26, 26, operative in bearings formed in the bottom ends of the 10 locking strips 13. The ring is normally held out of engagement with a supporting ledge 27 formed on the bottom of the back's concavity by a spring rod 28, operating through a cross brace 29. The ring 25 is pushed 15 down against the action of its spring rod 28 by the core, when it is in casting position, so that ledge 30, formed about its periphery, engages on top of the ledge 27 on the back, thus forming a means for supporting the 20 core in casting position. The aforesaid ledge 27 on the back also serves as a positioning means for the bottom edge of a flexible matrix M when positioned in the back. (See Fig. 5.)

25 A convex casting core 40 is positioned directly in front of the concavity of the back 10, and is arranged so that its convex face can be moved from a horizontal position (shown in Fig. 1) to a vertical position 30 within the concavity of the back, as shown in Fig. 2.

The core 40 is mounted on and fast to a core operating carriage 41, the supporting wheel 42 of which operates on top of a track 35 43, formed upon a track bracket 44, which is located in front of the back's concavity, and supported by two cross braces 45 and 46 fast in the side frames 11 and 12.

40 The core carriage 41 is formed with a longitudinal slot or guideway 47. Near the center of this guideway is the core supporting wheel 42, fast on a short cross shaft 48, which operates in bearings formed in the side walls of the core carriage and protrudes 45 beyond its outside faces and acts as a guideway and holding means as hereafter described.

The core 40 is caused to rock simultaneously with the movements of the core carriage wheel along the track, by connecting rods 49—49, one end of each of which rods is pivoted on a stud. These studs are fast 50 in bearings 50—50, formed on the lower end of the core carriage 41. The opposite ends 55 of the rod are pivoted on a short cross shaft 51, fast on the advance end of the track bracket 44.

The core is held in position on the track by faces of extensions 52—52, formed on 60 the guideway 47 of the core carriage, engaging each side of the track bracket 44, and the ends of the core wheel shaft 48, entering guideways 53—53, formed in the contiguous faces of brackets 54, fast at each 65 side of the track bracket.

The core is moved toward the back by the operator lifting up on the core handle 55, and at the same time it is turned by the connecting rods 49, until the bottom of the core enters the bottom ring 25, and becomes seated on a ledge 31 thereof. Simultaneously with the seating of the core on the bottom ring ledge 31 the ends of the connecting rods 49 engage on top of adjustable positioning stops 56—56, located in the cross brace 46. 70 In this position the core is at an angle away from the back of about 10% and the core carriage wheel 42, near the end of the track 43. From this position the core is pivoted upon the studs of the connecting rods 49, 80 to a vertical position, during which operation the core carriage wheel is swung free from the tracks. During this pivotal movement the bottom ring 25 is pressed down against the action of its spring rod 28, until 85 it becomes seated upon the ledge 27 formed within the back's concavity. The top end of the core is prevented from turning too far by a bar stop 57, fast on and extending across the flat side of the core, near its top, 90 engaging against the bolster packing strips 15—15, on the straight sides of the back.

95 During the entire turning operation the core carriage guideways hold the core in alignment and guide it into the vertical casting position. In this position it is locked by matrix clamping and locking strips 60—60, slidingly operative on studs 61 made fast in the flat side face of the core 40. See Figs. 2, 6 and 8.

100 Each locking strip 60 is caused to move in or out beyond the core's periphery by rock links 62—62, one end of each being pivoted to the locking strips and the opposite ends to slide connecting rods 63—63, 105 which operate in slide ways 64, aligned alongside the core operating carriage 41.

The two sliding connecting rods 63—63 are connected by a cross tie 65, extending through a bearing formed in a rock lever 66. 110 This rock lever 66 is pivoted on a stud 66 located across and near the upper end of the core operating carriage 41.

115 By thus joining the sliding connecting rods 63—63, they will act in unison with the rocking of the rock lever 66 and through the links 62 will push out the matrix clamping and core locking strips 60, beyond the periphery of the core, until the projections 67 thereon enter the recesses 14, formed in the 120 locking strips 13, and lock the core within the back's concavity. See Fig. 8.

125 In operating the casting mechanism the core is placed in a horizontal position. The matrix positioning slides 18 moved in so their advance ends are within the side edges of the back's concavity. The operator then forces a flexible matrix M into the back's concavity, above the slides, so that its vertical side edges will pass inside of them, and 130

then pushes it down the back and behind the slides until its bottom edge engages the top of the ledge 27, at the bottom of the back. The matrix is now in proper position for 5 casting, but to prevent metal passing behind the matrix a segmental pouring sheet 68 is provided, and positioned so that its bottom overlaps the top curved margin of the matrix, and extends upward to the top of the 10 back and is provided with supporting means consisting of projections 69 which engage over the top edge of the back. The segmental pouring sheet is more or less flexible and in length equal to the matrix.

15 Having positioned both the matrix and pouring sheet the operator rolls the core from its horizontal position into a vertical position within the back, thereby forming a curved casting chamber in which the matrix 20 and pouring sheet are positioned. The operator now closes the vertical side walls of the chamber by moving the rock lever 66 down, which action causes the combined matrix clamping and core locking strips 60 to push 25 out over the straight edges of the core and engage with their co-acting members on the back, and lock the core and back in casting position, at the same time clamping the raised side bolsters of the matrix.

30 During the advance movement of the locking strips their advance edges engage the advance edges of the positioning slides and force them back and out along their inclined planes sufficient to allow the locking projections to pass under. (See Figs. 8 and 9.)

The operator now fills the casting chamber with molten stereotype metal, either by means of a pump or ladle. After allowing sufficient time for the metal to solidify he 40 proceeds to remove the cast from the chamber by unlocking the core from the back and releasing the side bolsters of the matrix and drawing the locking and matrix clamping strips back. The operator now takes hold 45 of the core operating handle and rocks the core and stereotype plate cast thereon forward until the core carriage wheel brings up on top of the core track 43, during which operation the pivoted bolster packing strip 50 15 on the back pivots away from the straight sides of the back sufficiently to draw the slight projection 71 back and allow the matrix M to pass by along with the stereotype plate, which is carried by the core.

55 Continuing the delivery operation the core begins to pivot on its carriage wheel, which advances along the core track, during which the straight side edges of the stereotype plate come into engagement with the 60 top edges of plate lifters 72-72. These are pivoted on the cross brace 45 and come down on a cross rod 73 fast through the track bracket. Owing to the plate lifters' pivotal movement being eccentric with respect to 65 the movement of the core they force the

stereotype plate P free, and as the core rolls and advances, elevate it above the core's periphery and align it with guideways of the finishing mechanism. (See Figs. 1 and 3.)

Just previous to the straight edges of the stereotype plate engaging with the plate lifters, the extending ends of the core carriage wheel axle 48 pass into the guideways 53-53 formed in the guide brackets 54, and hold the core down against the lifting action 75 of the plate lifters. The plate lifters are supported in an engaging position by the cross rod 73.

After delivering the stereotype plate in the horizontal position, the operator removes 80 the matrix from the plate and, if a second cast is desired, repositions it in the back. He then removes the flexible pouring sheet and returns it to its position in the back.

The stereotype plate P is now pushed, by 85 the operator, forward and along the plate lifters on a pair of guideway brackets 80^a and 80, and into position beneath the shaving arch 81 of the finishing mechanism, in which position it is free from the core. 90

A positioning stop or ledge p is formed within the riser portion of each stereotype plate by a recess 76, made across the apex of the core. See Fig. 4. This ledge p engages against an adjustable stop 77, when 95 the plate is shoved into the finishing mechanism and positions the plate longitudinally therein.

The co-acting finishing mechanism, for truing out the interior surface of a series 100 of ribs cast beneath the type portion and separating the riser from the said type portion of the stereotype plate, is located in front of the casting mechanism. The stereotype plate finishing and supporting 105 arch 81, is mounted between the side frames 11 and 12, and in alignment with the stereotype plate guideways 80^a and 80, previously referred to. The finishing arch 81 is of a curvature equal to that of the stereotype 110 plate and is raised on the front side a little above the axis of a plate when delivered from the casting mechanism.

The plate is raised on the front side until firmly positioned against the concavity of 115 the arch by a plate elevator. The opposite side of the plate is supported by a bar 88, fast to the side edge of the arch, and in alignment with the guideway 80. The plate elevator comprises a plate supporting bar 120 89, which is aligned with the guideway 80^a, when in the lowered position. This supporting bar 89 is fast to a pair of brackets 90-90 which are fast on vertically disposed rods 91-91. These rods operate in brackets 125 92-92, fast to the front side frame 11, and in bearings 93-93, formed in the extending foot of the finishing arch. The bottom end of each rod 91 is provided with an antifriction roller 94, which operates on eccentric 130

face cams 95 made fast on a rock shaft 96 located in brackets 97—97, fast on the front side frame 11. To the rear end of this rock shaft is fixed an operating lever 98, for raising the elevator to clamp a stereotype plate against the concave face of the arch, while the finishing tools, consisting of a shaving knife and a planetary operation saw, shave and trim the aforesaid stereotype plate.

The shaving operation is accomplished by a knife 82 fast on a hollow knife shaft 83, which is axially aligned with the finishing arch 81 and supported in bearings 84 and 86, formed on cross frames 85 and 87. This knife shaft is driven through one revolution during each cycle of operations by a chain of reducing gears comprising a large gear 100, fast on the knife shaft near the forward bearing 86. The gear 100 is driven by a pinion gear 101, fast on the rear end of a short shaft 102, located in a bearing in the front cross frame 87. In front of this bearing, and on the short shaft 102, is fast a large gear 104 which is driven by a pinion 105 fast on the driving shaft 106. The gears 104 and 105 are protected by a gear cover 107, in which are bearings for their shafts, and is made fast to the end frame 87.

The trimming mechanism for separating the riser and beveling that edge of the plate is mounted on the knife shaft gear 100, and revolves with the knife shaft but around the periphery of a stereotype plate, whereas the knife revolves in its concavity. (See Figs. 2, 10, 11 and 12.) This mechanism comprises a planetary operating cutter or saw 110 fast to the rear end of a saw spindle 111. This operates in bearings formed in a segmental saw bracket 112, which is bolted to the rear side of the shaving knife gear 100. The forward end of the saw spindle 111 passes through an elongated opening in the body of the gear 100. (See Figs. 12 and 13.)

The trimming saw 110 is driven at a high rate of speed by a chain of gears consisting of a small pinion 113 fast on the forward end of the saw spindle which meshes with a pinion 114 mounted on a stud fast in the face of the shaving knife gear 100. This pinion 114 is driven by a larger gear 115, mounted loosely on the knife shaft between its gear 100 and its forward bearing 86. This gear 115 is driven by a large gear 116 fast on the rear end of the driving shaft 106. In operation the saw is driven at a high rate of speed and simultaneously revolved about the periphery of the riser portion of a stereotype plate, locked within the finishing arch. During this operation the saw separates the riser from the type portion of the plate and the shaving knife trues off

the ribs cast beneath the type face portion. 65 As the saw is revolving over and cutting off the riser from the type portion of the stereotype plate a riser support 120, fast on the knife beneath the riser, revolves up under the riser and holds it up. And at the same time the concave saw bracket 112 is passing over the outside of the riser. At the rear end of the concave saw bracket 112 is a pivoted door 122, the loose end of which engages on and is drawn over the face of 75 the riser until the saw has completed its separating operation, whereupon the riser begins to travel along with its support 120. As the revolution continues the riser is carried down and has a tendency to slide ahead 80 on its support, but is instantly checked by wedging between the pivoted door 122 and the riser support 120. But on the door's pivot passing the horizontal line it is overbalanced, and the riser and sawdust held in 85 the concavity of the saw bracket fall away from the mechanism.

The finishing tools and co-acting movable parts are driven by a belt 130, alternating between a tight and loose pulley 131 and 90 132, which are mounted on the forward end of the driving shaft 106. The shifting of the driving belt is accomplished by an automatic belt shifter 133, which is controlled by a hand operated trip. The belt shifter 95 133 is fast to the bottom end of a vertical pivot shaft located in a bracket 134. To the top end of this pivot shaft, and above the bracket bearing, is fast a trip arm 135, which is engaged by a right angular extension 136, of a trip rod 137, axially located in the hollow of the shaving knife shaft 83, and slidingly operative in bearings formed in each end of the hollow knife shaft.

The rear end of the trip rod 137 is provided with a grooved collar 138, in which are positioned projections on a pivoted yoke 139, made fast on a cross rock shaft 140, operative in bearings in the side frames 11 and 12. An operating lever 141 is fast on 110 the rock shaft 140 near its bearing in side frame 11. By swinging the operating lever 141 to the rear the right angular extension 136 of the trip rod 137 is drawn back from in front of the trip arm 135 of the belt shifter 115 which action allows the belt shifter to be drawn in by a spring 142, and move the belt from the loose pulley 131 to the right or operative pulley 132. This action starts the mechanism through its cycle of operations, and as it nears the end of the cycle the trip rod angular extension 136, which has been pushed forward by a spring 143, mounted on the rod 137, located in the hollow of the knife shaft, is revolved into position in front of the trip arm 135. As the revolving movement continues the right angular extension 136 engages and forces the 120 125

belt shifter to move the belt back to the loose pulley, against the action of the belt shifter spring 142.

Simultaneously with the return of the belt to the loose pulley, a brake shoe 144 attached to a short arm 145 formed on the belt shifter 133, is drawn into engagement with the face of the tight pulley and instantly stops the operations.

10 To prevent the accidental starting of the finishing mechanism before the plate is elevated into operative position there is provided a stop 146 formed on the lower end of the starting lever 141, which engages 15 against a cam plate 147 formed on the hub of the plate elevator operating lever 98. On elevating the plate lifter this cam plate turns out of the way and allows the stop 146 on the starting lever to pass. (See Figs 1, 20 2 and 10.)

After the stereotype plate has been finished by being shaved and trimmed, the operator lowers the elevator and draws the finished stereotype plate back and out of 25 the arch onto the guideways 80^a and 80 and removes it by hand.

No claim is made herein to the finishing mechanism by itself, as that forms the subject-matter of a divisional application, filed 30 September 25, 1922, Serial No. 590,274.

Although I have illustrated and described only a single form of the invention, yet I am aware of the fact that many modifications can be made therein without departing 35 from the scope of the invention as expressed in the claims. Therefore I do not wish to be limited to all the details of construction herein shown and described, but what I do claim is:—

40 1. In a curved stereotype plate making machine, a concave casting back and a convex casting core, plates located on the straight sides of the back for holding a flexible matrix in curved position against the back's 45 concavity, and means on the core for moving the plates out of engagement when the core and back are positioned to form a curved casting chamber.

2. In a curved stereotype plate making 50 machine, a curved casting back and a convex core, having matrix clamps, independent matrix guiding means located at each straight side of said back, and means for moving both of said guiding means into 55 position simultaneously.

3. In a curved stereotype plate making machine, a concave casting back, matrix guiding slides angularly disposed at each straight edge of said back's concavity, and 60 connections between said guides arranged to reciprocate the same simultaneously.

4. In a curved stereotype plate making 65 machine, a concave casting back, and matrix guiding means extending along each straight side of said back's concavity to guide and

align a flexible matrix as the same is moved longitudinally into casting position.

5. In a curved stereotype plate making machine, a concave back and a convex concave semi-circular ring pivoted at one end of the 70 back's concavity, a convex core supported in front of the back's concavity, and a spring arranged to hold the ring elevated above its pivot to engage one end of the core for the purpose.

6. In a stereotype plate casting device, the combination of a mold comprising two parts, one movable toward and from the other, with an end member for closing the mold, and yielding means for holding said end member toward the movable part, and means whereby when the mold is closed the end member will be moved back into its casting position by the weight of said movable part.

7. In a stereotype plate casting device, the combination of a mold comprising two parts, one movable toward and from the other, with an end member movable endwise in the mold for closing the mold and having 90 means thereon for clamping the edge of a matrix against one of said mold members when moved back to closed position, and yielding means for holding said end member at a distance from the end of the mold 95 and within it, whereby when the mold is closed the end member will be moved outwardly back into its casting position by the movement of the movable part.

8. In a curved stereotype plate making 100 machine, a concave back, a convex concave core, a single guide rail along which said core is adapted to move, and means movable with the core for holding it in position for the purpose set forth.

9. In a curved stereotype plate making machine, a stationary concave back, a single rail, a movable core operative over said single rail, and means for supporting the said core upon said rail for the purpose set 110 forth.

10. In a curved stereotype plate making machine, a vertically disposed concave back, a single guide rail centrally aligned with the back's concavity, a convex core carriage 115 operative over the said rail, and means for turning the said carriage for the purpose set forth.

11. In a stereotype plate casting device, the combination of a mold comprising a 120 main part and a movable part, a central guide rail, said movable part being movable along said rail, a rod pivoted at one end at a distance from said rail and having its other end pivoted to the end of the movable part of the mold, whereby as it moves along the rail it will be turned by the rod.

12. In a stereotype plate casting machine, the combination of a mold comprising a stationary part and a movable part, a rail, 130

a wheel movable on the rail, a carriage supported by the wheel and carrying said movable part, a rod connected with the end of said carriage and having the other end pivoted in a stationary position, whereby as the carriage moves toward the fixed mold member the movable part will be turned about the axis of the wheel.

13. In a stereotype plate casting device, 10 the combination of a stationary back and a movable core, with an end member in position to be engaged by the end of the core and moved back to casting position; a track, a wheel on said track for supporting said core, 15 said track, wheel and end member being relatively located to each other to permit the wheel to rest on the track until the core engages the end member and then cause the wheel to be lifted from the track as the core 20 is turned into its final position.

14. In a curved stereotype plate making machine having a concave back supported in a vertical position at one end, a core supporting and guiding rail located in front of the back's concavity, a core carriage engaging the sides of said rail, and means for causing the said carriage to turn simultaneously with its movement along said rail for the purpose set forth.

30 15. In a curved stereotype plate making machine, a vertically disposed concave back, a movable carriage upon which is fixed a

convex core, movable locking strips attached to the straight sides of the core, and means on the carriage for moving the strips for the 35 purpose set forth.

16. In a curved stereotype plate making machine, a casting back and a co-acting core, a matrix and core locking strip operative along the straight side of the core, rock links 40 pivoted to said strip, a connecting rod pivoted to the rock links, guideways in which the strip operates, and means for operating the strip for the purpose set forth.

17. In a stereotype plate casting machine, 45 the combination of a casting back and co-acting core, with a strip for locking the core and a matrix, said strip being located along the core, rock links pivoted to said strip for operating it, a connecting rod pivoted to 50 the rock links, and a pivoted member adapted to move said rod to operate the rock links and locking strip.

18. In a curved stereotype plate making machine, a concave casting back, and a co-acting core, a matrix and core locking strip at each straight side of the core, and connections independent of the core for operating the said strips in unison for the purpose set forth.

In testimony whereof I have hereunto affixed my signature.

CHARLES E. HOPKINS.
